PISTON CONSTRUCTION

William Wuerfel, Philadelphia, Pa., assignor to
Wilkening Manufacturing Company, Phila-
delphia, Pa., a corporation of Delaware

Application February 23, 1937, Serial No. 127,093

7 Claims.

(Cl. 309—12)

The present invention relates to a new and useful piston and piston construction, the lower or skirt portion of which is split longitudinally and is resiliently expanded, so as to cause the skirt to expand radially, and also relates to a new and useful method or process of making pistons so as to impart resiliency to the skirt portions thereof.

The object of the present invention is to provide a split-skirt type piston, wherein the skirt is caused to expand outwardly against the cylinder wall by a generally uniform and predetermined force, so as to prevent the skirt from collapsing or fluttering at high piston speed, and so as to maintain the skirt in a generally round or circular formation.

With the above and other objects in view, which will appear more fully from the following detailed description, the present invention consists in longitudinally slotting or splitting the skirt or lower portion of the piston, from its lowermost edge up to some point beneath the bottom ring-receiving groove, then slotting the skirt also transversely to a suitable extent at the upper end or head end of the longitudinal slot or split, so as to permit a certain amount of expansion and contraction in the split portion of the skirt, providing suitable grooves in the juxtaposed split edges of the skirt, and so positioning a generally corrugated flat spring member in said groove, as to cause the same to exert a generally tangential force upon the two longitudinal split edges of said skirt, in opposite directions, so as to tend to expand said skirt.

The present invention further consists of other novel details of construction, all as will more fully appear from the following detailed description.

For the purpose of illustrating the invention, there is shown in the accompanying drawing forms thereof which are at present preferred, since the same have been found in practice to give satisfactory and reliable results, although it is to be understood that the various instrumentalities of which the invention consists can be variously arranged and organized and that the invention is not limited to the precise arrangement and organization of the instrumentalities as herein shown and described.

Referring to the drawing in which like reference characters indicate like parts:

Figure 1 represents a front elevational view of a piston embodying the present invention.

Figure 2 represents a bottom plan view of the same.

Figure 3 represents a plan view on an enlarged

scale of the corrugated spring member taken on line 3—3 of Figure 1.

Figure 4 represents a section on an enlarged scale taken on line 4—4 of Figure 1.

Figure 5 represents a section taken on line 5—5 of Figure 3.

Figure 6 represents a perspective view of the corrugated spring member shown in Figure 1.

Figure 7 represents a front elevational view of an alternative corrugated spring member in its operative position.

Figure 8 represents a front elevational view of another alternative corrugated spring member in its operative position.

Figure 9 represents a section taken on line 9—9 of Figure 8 on an enlarged scale.

Figure 10 represents a perspective view of the corrugated spring member illustrated in Figure 8.

The piston 11, of the present invention, may be of any suitable type, and formed of any suitable metal, having any suitable number of ring-receiving grooves 12 and having a lower skirt portion 13, and wrist pin bearings 14 and 15 formed integrally with the piston.

Intermediate the pair of wrist pin bearings 14 and 15, a relatively narrow parallel portion of the piston skirt 13 is removed by any suitable cutter, or the piston may be formed initially with the slight gap or space 16 in the skirt 13. This leaves the skirt split along one generally longitudinal line. A transverse slot 17 is also provided in the skirt, at the upper end of the gap or slot 16, so as to give the two halves of the skirt, on either side of the slot 16, greater freedom of expansion and contraction.

In the juxtaposed edges 18 and 19 of the skirt slot 16 corresponding grooves 20 and 21 are provided by means of any suitable rotary tool. This tool may include a shank portion adapted to be gripped in any milling machine and a rotary cutter having opposite cutting edges. The tool may be rotated at a suitable speed in the head of the milling machine and the cutting edge then fed through the slot 16 in a direction generally parallel to the slot so as to form the opposed grooves 20 and 21 in the free edges of said slot. The expander spring 22 illustrated in Figures 1 to 6 inclusive is formed of any suitable flat ribbon type spring metal of suitable thickness and is formed with generally similar corrugations 23. The front or radially outermost portion of the spring member 22 is extended into the slot 16 and alternately contacts slot edges 18 and 19 at the peak of each wave or corrugation of the

spring 22. Slight longitudinal projections 24 are provided along the front edge of the spring 22, and these projections cooperate with the slot grooves 20 and 21 thus serving to lock the spring 22 in the slot 16 in a radial direction. These longitudinal projections 24 are preferably formed from and stamped out of the spring member 22 in such a direction as to cause them to extend beyond the crest or peak of each of the individual waves or corrugations 23. The spring 22 is locked in the slot 16 against longitudinal displacement and prevented from sliding out of said slot by means of a transverse projection 25 which is formed integrally with and stamped out of the upper end of the spring 22. The spring 22 is inserted in the slot 16 by merely slipping it in at the lower end thereof, then the front longitudinal projections 24 of the spring 22 are forced into the grooves 20 and 21 until the uppermost spring projection 25 snaps into the transverse slot 17. In this position, the lower edge of the upper spring projection 25 overhangs that portion of the lower surface of the upper transverse slot 17 that is adjacent and abuts the upper extremity of the longitudinal slot 16. When thus snapped in place, this spring 22 is effectively locked against longitudinal displacement, the reciprocation of the piston then having no effect upon the security of the spring in the piston.

30 The transverse overall dimension of the spring 22 in its normal or unstressed condition (excluding its projections 24) is greater than the normal distance between the juxtaposed edges 18 and 19 of the slot 16 by an extent sufficient to tension the spring 22 when inserted in said slot 16 to the desired extent.

When the spring 22 is inserted between the edges 18 and 19 of the slot 16, the spring is tensioned transversely and exerts a tangential force generally equal to this tension. This tangential force exerted generally uniformly throughout the length of the slotted portion of the skirt 13 causes this skirt to be expanded against the cylinder wall so as to prevent the collapsing of the piston skirt and to prevent the flutter of the piston skirt at high speeds. This also tends to expand the skirt under all operating conditions.

In the modified form of the present invention illustrated in Figure 7, the upper transverse spring projection 26 is formed or bent on the same side of the spring 22 as is the adjoining longitudinal spring projection 24, as distinguished from the type shown in Figures 1 to 6 inclusive in which the upper transverse projection 25 has been bent away from the spring 22 in a direction opposed to that in which its adjoining longitudinal projection 24 has been bent. The particular direction in which the upper transverse spring projection may be bent is optional, the important feature being that the underside of this projection should extend sufficiently far beyond the body of the flat corrugated spring so as to contact a sufficient portion of the lower side wall of the upper transverse groove 17 to retain the spring in the skirt slot 16 against longitudinal displacement.

In the other alternative embodiment of the present invention illustrated in Figures 8, 9 and 10, a flat corrugated spring 22 is provided with a series of alternately opposed projections 27 extending along the radially outermost edge of the flat spring member. These projections are equally distributed along the longitudinal edge of the spring and are so located with respect to the 75 spring corrugations as to be disposed at the crest

of each individual corrugation and are so formed as to project beyond said crest. These projections 27 are preferably formed integrally with the corrugated spring. Thus, the spring member may originally be stamped out of any suitable metal with the tongues 27 all extending beyond one edge of the spring and in the same plane as that of the spring body itself. These tongues or projections may then be alternately bent in opposite directions so as to lie in a plane generally perpendicular to the flat sides of the spring and this spring may then be corrugated in the manner shown in Figure 10, or if desired the flat spring may first be corrugated and then these projections bent in opposite directions. It is important that this spring be so arranged that these projections 27 each project beyond the highest point of its associated individual corrugation. As illustrated in Figures 8 and 9, these projections 27 may then readily enter into the opposed 20 grooves 20 and 21 formed in the edges 18 and 19 of the longitudinal piston skirt slot 16.

In this particular embodiment of the present invention, the upper end 28 of the spring 22 is extended slightly beyond the general outline of 25 the spring so as to cause said end 28 to project into the transverse slot 17 to a suitable extent thereby locking the spring 22 in the grooves 20 and 21 and preventing it from sliding out. The spring illustrated in Figures 8 to 10 inclusive may 30 be inserted into the longitudinal piston skirt slot 16 by aligning the spring projections 27 with the slot grooves 20 and 21, and then forcibly slipping the spring in said slot at the lower end thereof until the upper overhanging end 28 is snapped 35 into the transverse slot 17. In this position, the reciprocation of the piston does not effect the longitudinal security of the spring in said piston.

In all the embodiments of the present invention illustrated in the drawing, the spring member 40 22 extends from the grooves 20 and 21 of the piston slot radially inwardly, and thus part of the spring 22 projects radially inwardly beyond the periphery of the inner piston wall, but no part of the spring 22 contacts the cylinder wall.

It is to be noted that in neither of the embodiments illustrated do the longitudinal spring projections 24 or 27 extend sufficiently far into the slot grooves 20 and 21 to contact the innermost surface thereof. As a result, the expansive force is exerted by the body of the spring 50 contacting the slot edges 18 and 19, rather than by the spring projections 24 or 27 contacting the innermost groove surfaces.

The present invention may be embodied in 55 other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what is hereby claimed as new and desired to be secured by Letters Patent is:

1. A piston having a generally cylindrical skirt radially bounded by inner and outer generally cylindrical surfaces, said skirt being slotted generally longitudinally and having opposed parallel grooves in the juxtaposed faces of said longitudinal slot intermediate said inner and outer generally cylindrical surfaces of said piston skirt, and of a transverse width substantially less than the principal radial thickness of the major portion of the skirt, the longitudinal slot in said skirt 70 75 75

extending radially through the skirt wall so as to permit free radial movement of the skirt-portion on each side of the slot with respect to the skirt portion on the other side of the slot; and a corrugated ribbon-like spring member formed from flat spring metal operatively interposed between the two juxtaposed sides of said longitudinal slot with its convolutions extending generally tangentially of the skirt, and in operative engagement with said grooves, tending to exert opposed tangential forces upon said skirt to expand the same.

2. A piston having a generally cylindrical skirt radially bounded by inner and outer generally cylindrical surfaces, said skirt being slotted generally longitudinally and having opposed parallel grooves in the juxtaposed faces of said longitudinal slot intermediate said inner and outer generally cylindrical surfaces of said piston skirt, and of a transverse width substantially less than the principal radial thickness of the major portion of the skirt, the longitudinal slot in said skirt extending radially through the skirt wall so as to permit free radial movement of the skirt portion on each side of the slot with respect to the skirt portion on the other side of the slot; and a corrugated ribbon-like spring member formed from flat spring metal operatively interposed between the two juxtaposed sides of said longitudinal slot with its convolutions extending generally tangentially of the skirt, tending to exert opposed tangential forces upon said skirt to expand the same, and in operative engagement with said grooves and with the median portions of said corrugated spring being radially unbounded and clear of the piston skirt wall.

3. A piston having the skirt portion thereof slotted generally longitudinally so as entirely to disconnect the two parts of the skirt on either side of the slot in the zone of the slot and so as to permit the independent radial expansion and contraction of the skirt portions on either side of the slot, recesses formed in the juxtaposed sides of said longitudinal slot, a generally corrugated ribbon-like spring member formed from flat spring metal operatively interposed between the two juxtaposed sides of said generally longitudinal slot with its convolutions extending generally tangentially of the skirt, said spring member including means extending into and coacting with said recesses for retaining said spring member against generally radial displacement in relation to the piston skirt, and including means in interlocking engagement with said piston to retain said spring member against generally longitudinal displacement in relation to the piston skirt.

4. In a piston having a generally cylindrical skirt radially bounded by inner and outer generally cylindrical surfaces, said skirt being slotted generally longitudinally and having opposed parallel grooves in the juxtaposed faces of said longitudinal slot intermediate said inner and outer generally cylindrical surfaces of said piston skirt; said grooves being of a transverse width substantially less than the principal radial thickness of the major portion of the skirt; the longitudinal slot in said skirt extending radially through the skirt wall so as to permit free radial movement of the skirt portion on each side of the slot with respect to the skirt portion on the

other side of the slot, a generally corrugated ribbon-like spring member formed from flat spring metal and adapted to be operatively interposed between the two juxtaposed sides of said longitudinal slot to exert opposed tangential forces upon said skirt to expand the same, said spring member being adapted operatively to engage with said grooves and having its convolutions extending generally tangentially of said skirt.

5. In a piston having the skirt portion thereof slotted generally longitudinally so as to permit expansion and contraction of said skirt; and having the skirt wall portions immediately marginal to said slot of generally the same over-all radial thickness as the principal radial thickness of the major portion of the skirt-wall, a generally corrugated ribbon-like spring formed from flat spring metal and adapted to be operatively interposed between the juxtaposed edges of said slot and having its convolutions extending generally tangentially of the skirt to cause said skirt to expand by opposed tangential forces exerted by said spring; portions of the spring being adapted to interlock with portions of the piston for preventing radial displacement of the former with respect to the latter, and interlocking means for preventing the axial displacement of the spring with respect to the piston.

6. In a trunk type piston having a skirt slotted generally longitudinally and having a transverse slot communicating with the inner end of said longitudinal slot (that is, nearest the head-end of the piston) and having the skirt wall portions immediately marginal to said longitudinal slot of generally the same over-all radial thickness as the principal radial thickness of the major portion of the skirt-wall, a generally corrugated ribbon-like spring member formed from flat spring metal and adapted to be operatively interposed between the two juxtaposed edges of said longitudinal slot and having its convolutions extending generally tangentially of the skirt to exert opposed tangential forces upon the two opposed sides of said skirt on either side of said slot; portions of the spring member being adapted to interlock with portions of the piston for preventing radial displacement of the former with respect to the latter, and interlocking means for preventing the axial displacement of the spring member with respect to the piston.

7. In a piston having a skirt slotted generally longitudinally and having the skirt wall portions immediately marginal to said slot of generally the same over-all radial thickness as the principal radial thickness of the major portion of the skirt wall, a groove provided in each of the opposite side-walls of the slot in said skirt, a generally corrugated ribbon-like spring member formed from flat spring metal and adapted to be operatively interposed between the slot edges of said skirt and having its convolutions extending generally tangentially of the skirt, said spring member being adapted to be partly disposed within said grooves to interlock with said grooves so as to prevent displacement thereof with respect to the piston skirt in a radial direction, without restraining the independent radial expansion and contraction of the skirt portions on opposite sides of the slot.
